SHARPENING DEVICE FOR THE CUTTING
ROLLERS OF PENCIL SHARPENERS

Fred E. Bearden, Spartanburg, S. C.

Application July 31, 1946, Serial No. 687,493

2 Claims. (Cl. 51—250)

1

This invention relates to a pencil sharpener and more especially to a sharpener which has a stand having a shaft mounted therein, and the stand has an internal gear which meshes with pinions mounted on a pair of cutting rollers mounted laterally of the shaft so that turning of the shaft imparts rotation to the cutting rollers and the pencil is inserted between the cutting rollers to sharpen the same. This type of sharpener is also equipped with a housing surrounding the cutting rollers for catching the shavings from the pencil while it is being sharpened.

It is the purpose of this invention to provide a sharpener, which can be inserted over the cutting rollers after the shaving case has been removed so that by reversely turning the handle which drives the sharpening rollers and driving them in a reverse direction, the rollers will be sharpened over their bevels, that is, the rollers will be turning reversely and will not be engaging the sharpening means in the same manner as they would engage a pencil in a forward cutting motion.

It is an object of this invention to provide a sharpening mechanism adapted to be inserted over the sharpening rollers and having resilient means for holding the same in position and having an abrasive portion adapted to be pressed against the sharpening rollers by the resilient means, and whereby the sharpening rollers can be driven in a reverse direction for a plurality of times to sharpen the cutting rollers. Then the sharpening mechanism can be removed and the shavings case reinserted and the sharpener is then ready to use with sharpened rollers to provide a very much better sharpening of the pencil than would be possible if the rollers were dull.

It is another object of this invention to provide a sharpening means adapted to be attached over and resiliently held against the sharpening rollers in a pencil sharpener so that by reverse turning of the sharpening rollers, the cutting edges will be sharpened.

Some of the objects of the invention having been stated, other objects will appear as the description proceeds, when taken in connection with the accompanying drawings, in which:

Figure 1 is a side elevation of a pencil sharpener with the sharpening mechanism shown in vertical section and attached thereto;

Figure 2 is a front elevation looking from the right hand side of Figure 1;

Figure 3 is a vertical sectional view taken along the line 3—3 in Figure 1;

2

Figure 4 is an isometric view of the U-shaped member associated with the sharpening means for mounting the sharpening means on the sharpening rolls;

5 Figure 5 is a sectional view taken along the line 5—5 in Figure 1.

Referring more specifically to the drawings, the numeral 10 indicates a shank or stand, which is adapted to be secured to any suitable support by means of suitable screws, not shown, penetrating its base 11. The upper end of this shank has a circular portion 12, which has an internal gear 13 and a plurality of grooves 15 into which the prongs on the shaving casing, not shown, are adapted to be inserted for securing the shaving casing in position.

The stand 10 also has a tubular portion 14 extending therefrom, in which a shaft 16 is rotatably mounted having a crank handle 17 secured on one end thereof, and being flattened and separated, as at 18 and 19 near its other end, and terminating in a flattened portion 20 having a circular hole 21 therein through which the pencil to be sharpened is adapted to be inserted after passing through an opening in the shaving container, not shown. The shaft 16 is enlarged, as at 9, immediately inside the internal gear 13 and has fixed therein one end of shafts 25 and 26 on which sharpening rollers 22 and 23 are rotatably mounted, the other ends of the said shafts being mounted in the outer end of portion 20. Rollers 22 and 23 are rotated by gears 39 and 40 mounted thereon and revolving in internal gear 13.

35 The above described mechanism is conventional in the above-described type of sharpener, and is only described to show in what manner my sharpening mechanism cooperates with this type of sharpener. My sharpening mechanism 40 comprises a U-shaped bracket 30, having legs 31 and 32 joined together by a bottom piece 33 and the legs 31 and 32 have notches 34 and 35 therein, which are adapted to fit over one of the portions 18 or 19 of the shaft 16. To the base portion 33, I secure by any suitable means, such as rivets 36, an elastic band 37, and on the interior of a portion of this elastic band I adhesively or otherwise secure an abrasive member, such as emery cloth 38. The bracket 30, the elastic band 37, and the abrasive member 38 rotate with the shaft 16. In use of this invention, the shavings casing is removed and the notches 34 and 35 are inserted over either of the portions 18 or 19

50 and the elastic band 37 is distended to cause the

abrasive sheet 38 to fit against the cutting rollers 22 and 23.

In normal operation of the pencil sharpener in sharpening a pencil, the handle 17 is turned in a counter-clockwise manner in Figure 2, and the cutting rollers 22 and 23 are driven in a clockwise manner in Figure 2 due to their pinions engaging with internal gear 13.

When the sharpening mechanism is placed on the rollers as shown in the drawings, the handle 17 is turned in a reverse direction, or a clockwise manner in Figure 2, which drives the cutting rollers backward and causes them to have their sharpened spiral cutting edges driven in a reverse direction to thereby cause the sharpening effect to be properly applied in applying the abrasive action to the top sloping surface of the cutting edges instead of tending to dull them by driving them in the same manner as they would be driven if they were used in sharpening a pencil.

It is thus seen that I have provided a sharpener for the cutting rolls of a pencil sharpener which can be quickly installed for a sharpening operation, and just as quickly removed when the cutting rollers have been properly sharpened.

In the drawings and specification, there has been set forth a preferred embodiment of the invention, and although specific terms are employed, they are used in a generic and descriptive sense only, and not for purposes of limitation, the scope of the invention being defined in the claims.

I claim:

1. A sharpening device for cutting rollers of a pencil sharpener comprising a stand and an in-

ternal gear and a shaft mounted for rotation in said stand, and having a pair of spaced cutting rollers rotatably mounted in the shaft, said cutting rollers having pinions thereon adapted to engage said internal gear to impart rotation to the same, comprising a bracket insertable against said shaft and having resilient means mounted on the bracket, said resilient means being adapted to encircle the cutting rollers and having an abrasive substance thereon and adapted to be held in contact with the surfaces of the cutting rollers by means of said resilient means.

2. A sharpening device for the cutting rollers of a pencil sharpener comprising a frame fixed on a rotatable shaft and having a pair of rotary cutting rollers mounted in the frame and spaced apart from each other, and having means for imparting rotation to the same, comprising an elastic band having an abrasive substance on its side next to the cutting rollers adapted to be placed in contact with the cutting rollers, and means adapted to be disposed between the elastic band and the frame for resiliently holding the abrasive surface in contact with the cutting rollers while they are rotating to sharpen the cutting surfaces of the cutting rollers.
